(57) **CLAIM**

The ornamental design for an electrical tester, as shown and described.

DESCRIPTION

FIG. 1 is a perspective view of the electrical tester according to a first embodiment of my design;

FIG. 2 is a front elevational view of the electrical tester shown in FIG. 1;

FIG. 3 is a top plan view of the electrical tester shown in FIG. 1;

FIG. 4 is a right side elevational view of the electrical tester shown in FIG. 1, with the left side elevational view being the mirror image of this FIG. 4;

FIG. 5 is a rear elevational view of the electrical tester shown in FIG. 1;

FIG. 6 is a bottom plan view of the electrical tester shown in FIG. 1;

FIG. 7 is a perspective view of the electrical tester according to a second embodiment of my design;

FIG. 8 is a front elevational view of the electrical tester shown in FIG. 7;

FIG. 9 is a top plan view of the electrical tester shown in FIG. 7;

FIG. 10 is a right side elevational view of the electrical tester shown in FIG. 7, with the left side elevational view being the mirror image of this FIG. 10;

FIG. 11 is a rear elevational view of the electrical tester shown in FIG. 7;

FIG. 12 is a bottom plan view of the electrical tester shown in FIG. 7;

FIG. 13 is a perspective view of the electrical tester according to a third embodiment of my design;

FIG. 14 is a front elevational view of the electrical tester shown in FIG. 13;

FIG. 15 is a top plan view of the electrical tester shown in FIG. 13;

FIG. 16 is a right side elevational view of the electrical tester shown in FIG. 13, with the left side elevational view being the mirror image of this FIG. 16;

FIG. 17 is a rear elevational view of the electrical tester shown in FIG. 13; and,

FIG. 18 is a bottom plan view of the electrical tester shown in FIG. 13.

In FIGS. 1-5, 7-11 and 13-17, a broken line representation of prongs is shown, which is for illustrative purposes only and forms no portion of the claimed invention.
